DESIGN FOR A CARD AND POKER CHIP HOLDER

Donald J. Smith, Los Angeles, Calif.

Application January 13, 1945, Serial No. 117,421

Term of patent 7 years

(Cl. D34—5)

To all whom it may concern:

Be it known that I, Donald J. Smith, a citizen of the United States, residing at Los Angeles, in the county of Los Angeles and State of California, have invented a new, original, and ornamental Design for a Card and Poker Chip Holder, of which the following is a specification, reference being had to the accompanying drawing, forming part thereof.

Fig. 1 is a perspective view of a card and poker chip holder in open position, embodying my new design;

Fig. 2 is a side elevational view thereof in closed position;

Fig. 3 is an end elevational view of the article in the position shown in Fig. 2; and

Fig. 4 is a top plan view thereof.

I claim:

The ornamental design for a card and poker chip holder, substantially as shown.

DONALD J. SMITH.
